HAND TOOL

Earl C. Applegate, Chicago, Ill.

Application March 31, 1952, Serial No. 279,673

7 Claims. (Cl. 51—187)

1

This invention relates to improvements in hand tools of the type wherein an abrasive coated strip of sandpaper or the like is held against the working face of a holder shaped to conveniently fit the hand of the user.

The primary object of the invention is to provide a simple, inexpensive, sturdy tool of this character which is readily grasped and to which the strip of sandpaper or the like may be applied quickly in a manner to be firmly held in desired position.

Other objects and advantages will become apparent as this description progresses and by reference to the drawing wherein:

Fig. 1 is a side elevational view of a tool embodying the features of this invention.

Fig. 2 is an end elevation of the same looking from the left of Fig. 1.

Fig. 3 is a vertical section taken on line 3—3 of Fig. 1.

Fig. 4 is a fragmentary side elevational view showing a slight modification of the right end portion of the tool illustrated in Fig. 1.

Fig. 5 is a side elevational view of a further modified form of tool according to this invention.

Fig. 6 is a fragmentary top plan view of the end portion appearing at the right of Fig. 5.

In the form shown in Figs. 1 to 4 inclusive, the tool comprises an elongated block having a flat bottom face 10 of generally rectangular plan and parallel side faces 11 and 12 rising upwardly from opposite longitudinal edges of the bottom face 10. Reference numeral 13 designates a transverse end face with which the bottom face 10 is joined to form an outwardly convexly curved junction. The end of the block opposite said end face 13 is defined by a relatively low face portion 14 rising perpendicularly from the bottom face 10 and an inwardly offset face portion 15 joined at its base with the upper limits of the face portion 14 by an upwardly facing ledge 16. The upper edges of the side faces 11 and 12 are joined by an upper face 17, with which the upper portions of the faces 13 and 15 form an outwardly convexly curved junction.

The bottom face 10 is preferably covered with a layer of resilient material 18, such as rubber, cork or the like.

A cylindrical bore 19 arranged approximately centrally of the top face 17 and bottom face 10 intersects the opposite side faces 11 and 12 of the tool. The bore 19 is of such diameter as to provide a chamber for the storage of a coil of abrasive coated strip material 20. A slot 21 extending angularly downwardly from the end face 13 and

intersecting the surface of the bore 19 nearest said end face 13 provides a passageway through which a free end portion of the strip 20 is adapted to be threaded and brought into a position to embrace the bottom face 10 and the covering 18 so as to overlap the forward face portion 14 and the ledge 16. The end of the strip 20 overlapping the ledge 16 is secured against the latter under pressure of a clamp having a jaw 22 joined as at 23 to a second jaw 24 slidably confined in a suitable recess 25 in downwardly spaced parallel relation to the ledge 16. A screw 26 adjacent to the end of the recess facing the joint 23 of the clamp provides a shoulder internally of the recess 25 engageable by a hump 27 formed in the jaw 24 to prevent accidental withdrawal of the clamp while permitting limited outward movement thereof to position the free end of the clamp jaw 22 clear of the path of the strip 20 overlapping the ledge 16.

Between the slot 21 and the portion of the top face 17 directly above the slot 21, the side faces 11 and 12 are pierced by a recess 29 to furnish a bearing parallel to the top face 17 in which the ends of a pair of arms 30 and 31 of a yoke-shaped clamping member are supported for rocking movement between an operative position straddling the ends of the bore 19 (as shown in full lines in Fig. 1) and an inoperative position upwardly of the recess 29 and outwardly of the end face 13 of the tool (as shown in dotted lines in Fig. 1). The swinging or free ends of the arms 30 and 31 are joined by a transverse bar 32 which in the operative position of the clamp acts to lock the strip 20 against a transverse groove 33 formed in the end face 13 located approximately midway of the slot 21 and the bottom face of the tool. The portion of the end face 13 above the groove 33 presents an outwardly offset shoulder about which the arms 30 and 31 are yieldably extendable to allow the bar 32 to be snapped into a seated position in the groove 33 and to be readily released therefrom when it is desired to relieve pressure on the abrasive strip 20.

The abrasive strip 20 is accordingly firmly held in taut relation to the resilient coating 18 on the bottom face 10 of the tool by the positive clamping action of the members 32 and 22.

Each end portion of the upper face 17 of the tool is provided with a depression 34 for engagement by a finger of the user so as to assure a secure and natural position for gripping the tool when either end of the tool is operated in a direction forwardly of the other end. A recess or depression 35 formed in each side face 11 and 12

and extending lengthwise of the tool affords further finger engagement to facilitate accurate manipulation of the tool.

Frequently, it is desirable to substitute a relatively hard backing or support for the abrasive strip rather than the resilient backing supplied by the coating 18. To this end the present invention contemplates a metal plate of such dimension as to present an area conforming to the contour of the bottom face of the tool and an auxiliary area forming an extension of said bottom face so as to provide a sharp angular nose or toe at one end of the tool. As shown in Fig. 1, the plate has a portion 36 forming an extension of the portion thereof overlying the face 10 of 15 the tool. This portion 36 terminates in a rearwardly and upwardly bent lip 37 engaging the face 14 whereby the strip 20 overlapping the face 14 is presented in the form of an acute angular nose to facilitate entry to work areas of restricted dimension not accessible to the face 14.

Fig. 4 indicates the position of the strip 20 overlapping the end face 14 when the metal plate is not used.

The modification shown in Figs. 5 and 6 illustrates the use of a tool having a bottom face 40 terminating at one end in a bullet-like nose 41 and at the opposite end in a seat 42 for the jaw 43 of a clamp having a second jaw 44 slidably confined in a recess 45 in the manner of the jaw 24 of the clamp shown in Figs. 1 to 4 inclusive. In this form of the invention, an abrasive strip 46 has one end thereof gripped by the jaw 43 at one end of the tool while the opposite end of the strip is confined in a downwardly and forwardly 35 slanting slot 47 formed in an upwardly facing ledge 48 at the opposite end of the tool. A rubber insert 49 provided in the nose of the tool provides a cushion for the portion of the abrasive strip overlapping the nose of the tool as well as a resilient or yieldable member which cooperates with the strip to maintain the same in a taut condition.

What is claimed is:

1. A hand tool comprising an elongated block 45 having a flat bottom face of generally rectangular plan and parallel side walls rising upwardly therefrom at opposite longitudinal edges thereof, said walls being joined at one end thereof by a transverse portion having an upwardly facing surface defining an upwardly exposed ledge intermediate the upper and lower limits of said walls, means for firmly securing a coated abrasive strip along said bottom face and in overlapping relation to said transverse portion and the upwardly facing surface of said transverse portion including a clamp having a jaw mounted for sliding movement in a fixed path perpendicular to said side walls and in spaced parallel relation to said bottom face and a jaw connected thereto adapted to engage a portion of the coated abrasive strip in underlying relation to said latter jaw.

2. In a hand tool as defined in claim 1 wherein in said jaw of the clamp in engagement with the coated abrasive strip is provided with reversely curved portions in the direction of its length.

3. In a hand tool as defined in claim 1 wherein in the first named jaw is mounted for sliding movement in a fixed path defined by a guideway formed in the body of the tool, and an abutment provided at the end of the guideway in the direction of the connection between said first named jaw and second jaw is engageable with an offset formed in said first named jaw to limit sliding movement of said jaws in a direction away from a position wherein the abrasive strip is engaged by said second jaw.

4. In a hand tool as defined in claim 1 wherein in said flat bottom face of the tool includes a layer of resilient material and a detachable member providing a relatively hard surface intermediate of said layer of resilient material and said abrasive strip.

5. In a hand tool as defined in claim 1 wherein in said flat bottom face of the tool includes a layer of resilient material and a detachable member providing a relatively hard surface intermediate of said layer of resilient material and said abrasive strip, said latter member having a coplanar extension terminating beyond the end limits of the side walls of the tool.

6. In a hand tool as defined in claim 1 wherein in said flat bottom face of the tool includes a layer of resilient material and a detachable member providing a relatively hard surface intermediate of said layer of resilient material and said abrasive strip, said latter member having a coplanar extension terminating in an acute angularly rebent nose portion beyond the end limits of the side walls of the tool.

7. In a hand tool as defined in claim 1 wherein in said ledge and the bottom face of the block have converging terminal portions cooperating with a resilient insert bridging said terminal portions to define a bullet-like nose.

EARL C. APPLEGATE.
